14 Claims. (Cl. 318—6)

1

The present invention relates in general to the handling of materials such as, for example, textiles; and more particularly to controls for moving the same in a predetermined relationship.

One object of the invention is to provide what may be termed a tensionless compensator or apparatus for maintaining material in a relatively slack condition. Another object is a method of handling moving materials in rope, web, sheet or other form wherein and whereby such materials may be processed free of tension. A further object is to control the movement of material from one place to another, or from station to station under predetermined and variable amounts of tension or without tension, as may be required. Another object proposed is means for automatically altering or changing the rate of speed at which such materials may be moved or processed. A further object is to control slack in a moving rope, web or sheet of material which changes its longitudinal dimension while being fed from a driven member or series of driven members to another driven member or series of members, as in a process for the production of textiles.

In textile practice, continuous movement of cloth goods through a series or range of treating apparatus units is common. For example, in a continuous bleaching or other similar process, the textile material while saturated with a caustic solution or with a bleaching solution is passed in rope form from the reel or rolls of one treating apparatus to the reel or rolls of another. Under the action of the caustic, or in the case of bleaching solution, merely because of the wetting, the material undergoes a change in its longitudinal dimension, which, due to the variable nature of textile products, does not occur at a fixed rate. In such cases it has been found very desirable to maintain a slack loop in the textile material as it moves between the two reels.

The present invention proposes an apparatus and means for holding the material slack by maintaining the speed of rotation of one reel constant while varying the rotational speed of the other reel, and controlling the variation in speed of the second reel, by some means sensitive to the results obtained. One obvious example of such a means would be an operator stationed beside the machines with instructions to speed up the motor actuating the variable speed reel if the slack became too great, or to slow it down if the slack became too little. Another means might be photoelectric cells. Such cells will control the flow of current in a circuit in response to variations in a focused beam of light directed at them. When used with sheet material, it is a simple matter to arrange the cells and the light sources so that the broad surface of the material intersects the beam of light. However, a roped fabric, viewed from almost any direction, presents

2

the same relatively small amount of cross-sectional area. Thus no matter how the cells and light sources are located, only a small area can intersect the beam of light. Furthermore, as the material moves through the loop, it sways from side to side, since there is no reason or means to restrict it, and since such motion may be imparted to it by the apparatus; the loop will also sway forward and back in the general direction of motion and directly opposed to it; and the loop will rise and fall as the speed of the variable reel is changed. Thus the loop is free to move in almost any direction. It is this random movement of the loop, together with its relatively small cross section, which makes an ordinary installation of photoelectric cells unreliable or unsatisfactory. In the present invention, however, an automatic contact controller is employed to maintain slack in traveling material as may be desired within predetermined limits; and said controller is operable whether the material be arranged in open width, in rope form, or otherwise.

With the above and other objects in view, as will be apparent, the present invention consists in the construction, combination and arrangement of parts, all as hereinafter more fully described, claimed and illustrated in the accompanying drawings, wherein:

Fig. 1 schematically illustrates a portion of the apparatus used in a continuous bleaching operation for textiles in combination with one embodiment of the present controller;

Fig. 2 is an electrical diagram showing the circuits of the controller when applied to a D. C. motor, such as, for example, the plaiter motor of Fig. 1;

Fig. 3 is a side elevation of a ratchet relay adapted for use in the present invention;

Fig. 4 is an elevation showing the opposite side of the relay shown in Fig. 3; and

Fig. 5 is an end elevation showing the ratchet mechanism of the relay of Fig. 3.

As previously stated, the present invention contemplates means for maintaining moving material in a slack condition, at least between selected points or stations, and is believed to be particularly adapted to textile operations—especially, for example, in finishing treatments of woven piece goods or knit goods. One such application in the textile field wherein the invention has been found useful is in a process sometimes referred to as continuous bleaching. In that type of process, a theoretically endless length of textile material, either in rope or web form, is successively and continuously moved or passed through a series or range of treating units. That is to say, the material may, for example, be continuously and uninterruptedly fed in rope form from a storage bin to wash box; thence successively through a J-box steamer, a pit saturator, squeeze rolls, a

second washer, a second J-box, a washer saturator, and finally to a hand truck for further disposal. During this relatively extensive series of cloth treatments, the moving material is moistened and/or wetted and usually is subjected to the action of chemicals such as caustic or peroxide. These factors tend to shrink the fabric being processed, both widthwise and longitudinally. Shrinkage in length becomes a problem, because tension is required to pull or move the fabric through the processing apparatus, and with the concomitant longitudinal shrinkage caused by chemicals and/or moisture, as described, the normal amount of tension is thereby increased and magnified, often above and beyond satisfactory limits. This difficulty is often acute in the bleaching or other treatment of rayons, which have an inherently low wet strength and in the moist state are subject to tearing under excessive strains or tension.

The present invention, therefore, contemplates means for preventing undesirable tension in textile material as, for example, by establishing and maintaining slack therein during a pre-determined part or portion of its travel lengthwise through a continuous range of operations. To that end, there is proposed a control unit or controller device suitably mounted in or adjacent the range of treating apparatus and adapted to alternately retard or advance within pre-determined limits, as may be required, the speed at which a continuously moving length of material passes a given point in the range.

More particularly, a loop may be established as the moving textile material passes at a given or constant rate of travel from one machine or apparatus to another, say, for example, from the squeeze rolls at the delivery end of a saturator to an adjacent J-box steamer. This loop may be suspended at its opposite ends from reels on the adjacent machines. Its depth, that is the specific amount or degree of slack in the loop, is controlled between predetermined upper and lower limits. When the bottom of the loop reaches or contacts the lower limit, a ratchet relay is actuated to cut in extra resistance in the field of a variable speed D. C. shunt motor (if that particular type of motor be employed), controlling the rate at which the material passes through the exit portion of the loop, thereby speeding up the motor and the passage of the material at that point, and decreasing the depth of the loop. Thus the extent of the loop or the amount of slack in the moving material is gradually reduced until a predetermined upper limit is reached. At that time, by contact of the material with the upper limit, the relay operates again and is actuated to cut out the extra resistance, thereby slowing up the variable speed motor and causing the loop to drop gradually or increase its depth to increase the amount of slack in the fabric or material. Thus there is provided controller means for continuously moving the fabric from one station to another in the slack condition in combination with means for adjusting the amount or degree of slack therein.

The operation of the ratchet relay above mentioned is controlled electronically. A second relay is in the plate circuit of a cold cathode tube. The starter anode circuit is broken and one side is attached to any metallic roll or pot eye with which the cloth is in contact on either machine. The other side is attached alternately to an upper or lower electrode marking the upper or lower limits of the loop. The ratchet relay shifts con-

trol from one electrode to the other as the loop rises and falls. As the cloth comes in contact with one or the other of these electrodes, the starter anode circuit is completed, thus firing the tube and causing it to conduct. The relay in the plate circuit then closes, operating the ratchet relay which performs a double function, namely, it changes the resistance of the motor field, causing the speed of the variable speed motor to change, and it also transfers control from one to the other of the limiting electrodes, at the same time extinguishing the tube and opening the plate circuit relay. Furthermore, means are provided, as will be apparent, to insure that the ratchet relay has sufficient time to make a complete cycle.

Referring now to the drawings:

The present invention may be employed in advancing a continuously moving length of textile material 10 in web, rope or other form, from between the squeeze rolls 11-12 of a saturator (not shown). A constant speed motor 13 may be mounted near the squeeze rollers 11-12 to move the web 10 at a uniform rate of speed from the rollers 11-12 of the saturator over a reel 14, also driven by the motor 13, into the zone where the present controller is effective to establish and maintain a loop 15 in the moving cloth 10 within the pre-determined upper and lower limits 16 and 17 respectively. Both limits 16 and 17 may be made of metal or other suitable material and constructed in the form of horizontally mounted and aligned fixed bars or metal idler rollers extending in spaced relationship laterally above and below the moving web 10. Preferably, the lower limiter electrode may be constructed in the form of a U-shaped pan which prevents the cloth descending to the floor when the apparatus is not in use. To prevent sudden increases in tension when the cloth touches the upper limit 16, the latter may be yieldably supported, so that it is capable of vertical movement or displacement upon contact with the cloth 10. If desired, a limit switch (not shown) may also be provided to shut down the range should the displacement of the upper limit or electrode exceed a predetermined amount.

Limits 16 and 17 are preferably electrically insulated from their supports and are connected through leads 18 and 19 respectively to an automatic controller 20. The controller 20 is connected through lead 21 to an idler roll 22. Thus the cloth 10 when it touches either limit 16 or 17 may complete the circuit with the controller 20 and cause it to operate.

The controller 20 is connected through leads 23 and 24 to a suitable A. C. supply (as shown), and through leads 26 and 27 to the field circuit of the motor 25. The controller 20, when activated by the cloth 10 acting through limits 16 or 17 and idler reel 22, functions to vary the resistance in the field circuit of the motor 25, varying its rotational speed. Further adjustment of the speed of the motor 25 is provided by the manual controller 28, a conventional variable resistor, connected by leads 26 and 29 to the automatic controller 20 and the line 31 respectively. Lines 30 and 31 represent a suitable D. C. supply for the motor 25. Lead 32 connects the armature circuit of the motor 25 to the D. C. supply line 31. As the cloth leaves the loop 15, it passes over the idler roll 22, and then on to the reel 33 and the plaiter 34, both driven by the variable speed D. C. shunt motor 25. From the plaiter 34, the cloth passes down in uniform plaits or folds into a steam J-box (not shown).

It is the motor 25, controlled by the device herein described, which is effective to maintain the slack loop 15 while transporting the cloth 10 through the apparatus shown. As shown in Fig. 2, the motor 25 is supplied from a suitable D. C. supply indicated by lines 30 and 31. The field winding 35 of the motor 25 is connected in series with the fixed resistance 36 and the manually adjustable controller, or resistor 28. The resistance 36 is connected at one end through the lead 37 to the flexible contact strip 78 of ratchet relay 41, part of auto-controller 20; at the other end it is connected through the lead 38 to the stiff contact strip 79 of the ratchet relay 41. Thus when the flexible contact strip 78 and the stiff contact strip 79 of the ratchet relay 41 are closed, the resistance 36 is short circuited or shunted out; when the flexible contact strip 78 is in the open position, the resistance 36 is effective in the field circuit of the motor 25.

The principal parts of the present controller 20 include the cold cathode tube 42, the relay 43 and the ratchet relay 41.

The cold cathode tube 42 is of the type which will pass a current from the cathode 44 to the plate or anode 45 only when the starter anode circuit is complete (including a suitable supply).

Relay 43 is of the conventional electromagnetic normally-open type with a single set of contacts 47 and 48 which remain open except when the coil 49 is energized. A condenser 50 is connected across the coil 49 to stabilize the voltage, and to keep relay 43 closed long enough to permit the ratchet relay 41 to make a full stroke. Coil 49 is connected at one end to the plate 45 of the tube 42, and at the other to line 23 of the A. C. supply. Thus when the tube conducts, the circuit, including line 24, cathode 44 and plate 445 of the tube 42, coil 49 of the relay 43 and line 23, is closed and contacts 47 and 48 of the relay 43 are closed; at other times they remain open. The contacts 47 and 48 when closed complete the circuit including the A. C. supply lines 23 and 24 and the coil 53 of the ratchet relay 41.

The ratchet relay 41, as indicated in Fig. 2 and shown in detail in Figs. 3, 4 and 5, employs an electromagnet together with a ratchet mechanism so constructed and arranged that each time the coil is energized the contacts are moved from one to the other of two alternate positions. An electromagnet 54, fixedly supported on base plate 55 with its axis perpendicular to the plane of the base, is energized by the coil 53, and acts on the armature 56. The latter is pivotally supported at 57 by the upright 58, which is fixedly supported by and perpendicular to the base 55. The supporting point 57 is near, but not at, one end of the armature 56, so that both ends of the armature are capable of motion toward or from the base 55. A vertically disposed spring 59, one end of which is secured to a projection of the upright 58, acts on one end of the armature 56 to pivot it about the point 57 and move it away from the magnet 54 when coil 53 is de-energized. An arm 60 projects at right angles from the upper end of the upright 58, to limit the motion of the armature 56.

A pawl 61 is pivotally supported at points 51 and 52 on the end of the armature 56 opposite that which is acted on by spring 59. A horizontally disposed spring 63, fixed at one end to a projection 64 on the armature 56, holds the pawl against the guide 65 which projects perpendicularly from the armature 56 at a point near the pivot points 51 and 52 so that the pawl 61

when at rest is almost perpendicular to the axis of the armature 56. The shaft 66 is rotatably supported parallel to the base 55 and between it and the armature 56, at points 67 and 68 by the fixed support 69. The axis of the shaft 66 is perpendicular to the plane in which the axis of the armature 56 moves. Ratchet wheel 70 is fixedly mounted on shaft 66 at a point directly opposite the armature 56 so that when the armature 56 is acted on by the electromagnet 54, it moves toward the shaft 66, and the pawl 61 engages the ratchet wheel 70, causing it to rotate and in turn rotate the shaft 66. An extension of the projection 64 also engages the ratchet wheel 70 when the armature is at the end of its stroke toward the shaft 66 and the electromagnet 54, to limit rotation of the ratchet wheel 70 to a single notch for each stroke of the armature 56.

20 A cam wheel 71, having uniformly spaced radially extending projections separated by an equal number of serrations or grooves, such that the total number of projections added to the number of grooves equals the number of teeth on the ratchet wheel 70, is fixed to one end of the shaft 66. A flexible follower strip 72, parallel to the base 55 and perpendicular to the axis of shaft 66 at the end on which the cam 71 is mounted, is fixed at one end to the projection 73 of the base 55, and has its other end free to move under the action of the cam. A projection 74 directed toward the cam 71 is located on the follower strip 72 directly opposite the axis of shaft 66. Projection 74 follows the cam 71 and flexes the follower strip 72. Thus when the electromagnet 54 acts on the armature 56, the pawl 61 engages the ratchet wheel 70 and advances it one notch. This rotates the cam wheel an amount corresponding to the angular distance from the center line of a serration to the center line of a projection. If the projection 74 were resting on a serration of the cam 71, a ridge then would move under it, lifting it and flexing the follower strip 72. The next time the electromagnet 54 is energized, a serration of the cam wheel 71 is moved under the projection 74. With further activation of the magnet, the cycle is repeated.

50 Stiff contact finger or strip 75, flexible contact finger 76, stiff contact finger 77, flexible contact finger 78 and stiff contact finger 79 respectively are mounted in parallel spaced relation above the follower strip 72 separated from the follower strip and from each other by flat insulating spacers. The ends of strips 75 to 79 corresponding to the fixed end of the follower strip 72 are fixed, and the other ends are free to move with flexure of the strips in a plane perpendicular to the base.

55 60 Flexible contact fingers 76 and 78 and follower strip 72 are longer than the stiff contacts 75, 77 and 79 and project beyond them at the ends adjacent the shaft 66. Insulating spacer 80 is fastened to the free end of flexible contact finger 78 and in operating contact with flexible contact finger 76. Insulated spacer 81 is fastened to the free end of flexible contact finger 76 and in operating contact with follower strip 72. Thus when the follower strip 72 is raised by the cam 71, flexible contact 76 is lifted by spacer 81, bringing it into contact with stiff contact finger 77, and flexible contact 78 is lifted by spacer 80 into contact with stiff contact finger 79. When a serration on the cam 71 moves under the projection 74 of the follower strip 72, the

follower springs back toward the cam, the flexible contact finger 76 moves from contact with stiff contact 77 into contact with stiff contact finger 75, and flexible contact 78 moves from contact with stiff contact finger 79 to the open position. When the electromagnet 54 is again energized, the cycle is completed; contact 76 moves into contact with contact 77 and contacts 78 and 79 close.

For purposes of explaining the operation of the control, let us assume that the control has just acted to slow down the motor 25 and shift control to the limit 17. The loop 15 falls until it touches the limit 17, at which time the cloth makes contact between the reel 22 and the limit 17, completing the circuit including the line 23, the resistance 83, the lead 84, flexible contact 76, stiff contact finger 77, lead 19, limit 17, the cloth 10, reel 22, lead 21, starter anode 46 and cathode 44 of the tube 42 and the line 24. This fires the tube 42, completing another circuit consisting of the supply line 24, the cathode 44 and plate 45 of the tube 42, the coil 49 of the relay 43 and the supply line 23, energizing the relay 43. This in turn closes the contacts of the relay 43 and completes a third circuit, including the supply line 23, contacts 47 and 48, coil 53 of the ratchet relay 41, and the supply line 24. This energizes the ratchet relay 41, causing the contacts 78 and 79 to open and the flexible contact 76 to shift from the position as shown in Fig. 2 touching contact 77 to a position touching contact finger 75. The opening of the contacts 78 and 79 cuts the fixed resistance 36 into the field circuit of the motor 25, speeding it up. The shift of flexible contact finger 76 from contact 77 to contact 75 of the ratchet relay performs two functions. It breaks the starter anode circuit of the tube 42, extinguishing it, thus opening contacts 47 and 48 of relay 43, and deenergizing coil 53 of the ratchet relay 41. Secondly, the shift of flexible contact finger 76 transfers control from limit 17 to limit 16. When, after a lapse of time, the cloth touches the limit 16, the tube is again fired and again activates the relay 43, closing it. This again activates the ratchet relay 41, which this time closes the contacts 78 and 79 and shifts the flexible contact 76 from contact finger 77 to contact finger 75. Closing contacts 78 and 79 shunts out the fixed resistance 36 in the field circuit of the motor 25, slowing it down. Shifting flexible contact finger 76 from contact 75 to contact 77 breaks the anode circuit and extinguishes the tube 42; at the same time it shifts control from the limit 16 back to the limit 17 to complete the cycle.

The second action of the ratchet relay, i. e., shifting control from the limit which has just activated the controller, is one of the more important features of the invention and one which makes it particularly suited to the applications in question. As the cloth travels in slack condition, it sways from side to side. The loop established by the slack will occasionally shift forward and back, i. e., the lowermost point of the loop will shift to left or right of the median of contacts 16 and 17 as shown in Fig. 1. Furthermore, the random roping of the cloth itself causes it to present a very uneven surface to the contacts. For these reasons a controller without the feature of the shifting control would, in this application, chatter incessantly. Shifting the control eliminates any effect from further impertinent contacts between the cloth and the contact roll once the controller has been activated, and forces

the cloth to pass through a complete cycle before the controller is again activated.

The circuits as shown in Fig. 2 are susceptible of slight modifications without altering the efficiency of the control. Thus with proper modification of the ratchet relay, the relay 43 may be omitted, and the ratchet relay 41 connected in its place in the plate circuit of the tube 42. In another modification, resistance 83 may be replaced by a voltage divider connected at one end to lead 23 and at the other to lead 24. Lead 84 would then tap the divider by means of an adjustable connection, in order that the voltage supplied to the cold cathode tube could be varied slightly.

The controller as set forth herein has several distinct advantages over similar devices. Since it operates on a very slight amount of electricity, (of the order of a small fraction of an ampere) a slight touch of the material to the contact is all that is required to set the control in operation—thus the control is quite sensitive to the movements of the slack loop. As explained above, due to the design of the contacts, the control is not affected by lateral motion of the slack loop. Due to the incorporation of the ratchet relay in the manner above described, the device is not overly sensitive to repeated slight contacts caused by the moving material, i. e., once the contact has been made and the tube fired, a full cycle must be completed before the same contact roll or limit can fire the tube again.

Reference has been made in the above description to cloth saturated with various solutions. It is customary in operations of the kind described to run the squeeze rolls of the saturator with a pressure setting sufficient to give 90% extraction, i. e., 90% by weight of moisture on the basis of the dry weight of cloth is present in the cloth as it leaves the rolls of the saturator. Such an amount of moisture is not necessary for the effective operation of the control, it being necessary only to have a slight amount of moisture present above the normal regain value of 9 to 15%.

The present controller has been described as applied to a variable speed D. C. motor moving roped moist cloth. Manifestly, it would work equally well with moist cloth in the open width, or with similar material, such as, for example, moist paper, or with any material capable of carrying the slight current involved; or a variable speed A. C. motor could be substituted for the shunt motor of the drawings. Or the two motors could be exchanged. That is to say, the constant speed motor may be employed to move the material as it leaves the slack loop. In this embodiment, the variable speed motor is employed to move the material into the slack loop. Another variation well within the scope of the present invention is the substitution in place of the variable speed motor shown of a constant speed motor with a variable speed drive such as a Reeves electric remote control, or a Reeves hydraulic control. In either case the subject control would be arranged to operate the pilot device of the variable speed drive.

What is claimed is:

1. A device for controlling an electric D. C. shunt motor, comprising a cold cathode tube, alternate means for completing the starter anode circuit of said cold cathode tube, a relay activated by the plate circuit of said tube, a second relay having a ratchet and controlled by the first relay, said second relay adapted to alternately in-

crease or decrease the resistance in the field circuit of said motor, and simultaneously shift the starter anode circuit of the cold cathode tube from one to the other of said circuit completing means.

2. In a device for feeding an endless length of material from one station to another, means for establishing and maintaining slack therein, comprising in combination a constant speed electric motor situated adjacent the first station, a variable speed motor adjacent the second station, a relay adapted to alternately increase and decrease the rotational speed of said variable speed motor, a second normally open relay activating said first relay, a cold cathode tube activating said normally open relay, a contact connecting the material to the starter anode of the cold cathode tube, and a plurality of additional contacts disposed above and below the path of the material whereby the material will complete the starter anode circuit of the cold cathode tube and activate the relays.

3. In a device for feeding an endless length of material from one station to another, means for establishing and maintaining slack therein comprising in combination, a constant speed motor at the first station, a variable speed motor at the second station, a relay adapted to alternately cut in and cut out a resistance in the circuit of the variable speed motor, a normally open type relay activating the first relay, a cold cathode tube activating said normally open relay, and contact means responsive to the position of the moving material, adapted to coact with the material and activate the cold cathode tube.

4. In combination, a constant speed motor moving an endless length of moist cloth into a zone of slack, a variable speed motor moving the cloth on out of the zone of slack, an electrical contact to connect the cloth to the starter anode of a cold cathode tube, two more contacts disposed one above and one below the path of the cloth and adapted to coact with the cloth and complete the starter anode circuit of the cold cathode tube, a normally open type relay controlled by the anode circuit of the cold cathode tube, and a second relay having a ratchet, and adapted to alternately increase or decrease the resistance in the power circuit of the variable speed motor, and simultaneously shift the starter anode circuit from one to the other of the contacts disposed above and below the cloth.

5. The combination with an apparatus for processing a moving length of moist cloth of means for establishing and maintaining slack therein comprising a constant speed motor to deliver the material to a given point, a variable speed motor to coact with the first motor and feed the cloth from the given point, and means subject to the motion of the cloth for controlling the speed of said second motor including a cold cathode tube, alternate contact means disposed above and below the moving cloth to coact with the cloth and complete the starter anode circuit of said cold cathode tube, a relay activated by the plate circuit of said tube, a second relay activated by the first relay, said second relay adapted to alternately increase or decrease the resistance in the motor circuit, and simultaneously shift the anode circuit of the cold cathode tube from one to the other of said contact means.

6. In combination, a constant speed motor adapted to move an endless length of moist cloth, a variable speed D. C. shunt motor adapted to coact with said constant speed motor and move

the moist cloth in slack condition, said variable speed motor having an armature and a field circuit, a variable resistor and a fixed resistor in said field circuit, a ratchet relay having contacts adapted to be alternately opened and closed connected in parallel with the fixed resistor, said relay having a magnetic coil, an armature acted on by the coil, and a pawl, ratchet and cam adapted to coact with the armature to operate the contacts, a circuit including a normally-open type relay, and a circuit including the cathode and starter anode of the cold cathode tube, a permanent contact for the moving cloth, alternate contacts above and below the path of the cloth adapted to intermittently coact with the cloth and activate the cold cathode tube thereby activating the relays, and a second set of contacts on the ratchet relay adapted to shift the starter anode circuit of the cold cathode tube from one to the other of the alternate contacts.

7. A device for controlling an electric D. C. shunt motor comprising a cold cathode tube, alternate means for completing the starter anode circuit of said cold cathode tube, a relay having a ratchet activated by the plate circuit of said tube, said relay adapted to alternately increase or decrease the resistance in the field circuit of said motor, and simultaneously shift the starter anode circuit of the cold cathode tube from one to the other of said circuit completing means.

8. In a device for feeding an endless length of material from one station to another, means for establishing and maintaining slack therein comprising in combination a constant speed electric motor to feed the material from one station, a variable speed electric motor to move the material into the receiving station, a power circuit for the variable speed motor including a fixed resistance, a ratchet relay having contacts and an electromagnetic coil, said contacts connected in parallel with the said fixed resistance, a normally open relay having an electromagnetic coil and contacts operated thereby, a circuit including the coil of the ratchet relay and the contacts of the normally open relay, a cold cathode tube having a starter anode circuit and a plate circuit, said plate circuit including the coil of the normally open relay, and contacts mounted adjacent the path of the moving material connected into the starter anode circuit of the cold cathode tube, whereby the material will complete the starter anode circuit of the cold cathode tube and activate the relays.

9. The combination with an apparatus for processing a moving length of material, of means for establishing and maintaining slack therein comprising a constant speed motor for moving the material beyond a fixed point, a variable speed motor constructed and arranged to coact with the constant speed motor and control movement of the material as it passes beyond the fixed point, and controller means for advancing and retarding the variable speed motor whereby the moving material may be held slack within predetermined limits, said controller means including a plurality of contact elements mounted above and below the path of travel of the material and adapted to intermittently engage the material, a cold cathode tube having a starter anode circuit and a plate circuit, said starter anode circuit connected to said contacts, a normally-open type relay the coil circuit of which is connected to the plate circuit of the cold cathode tube, a ratchet type relay the coil circuit of which is connected to the contacts of the normally open

relay, said ratchet relay being adapted to increase or decrease the resistance in the power circuit of the variable speed motor, whereby the contacts upon engagement with the moving material will activate the tube thereby activating the relays and varying the speed of the variable speed motor.

10. In a device for feeding an endless length of cloth from one station to another, the combination of a constant speed motor to deliver the cloth to a given point, a second variable speed motor to feed the cloth from the given point, an electromagnetic relay having a ratchet, pawl, and cam, and contacts operated thereby, one set of said contacts connected to the power circuit of said variable speed motor and adapted to increase or decrease the resistance in said power circuit, a second normally-open type electromagnetic relay the contacts of which are connected in series with the electromagnet of the ratchet relay, a cold cathode tube having a 20 starter anode circuit and a plate circuit, said plate circuit connected in series with the electromagnet of the normally open relay, a plurality of contacts disposed above and below the path of said cloth to coat with the cloth and complete the starter anode circuit of said cold cathode tube and activate said relays, and a second set of contacts on the ratchet relay adapted to shift the starter anode circuit of the cold cathode tube from one set to the other of said contacts above or below the path of the moving material.

11. In a device for feeding an endless length of material from one station to another, means for establishing and maintaining slack therein comprising in combination a constant speed driving means and a variable speed driving means arranged in tandem, a relay having an electromagnetic coil, an armature, cam, ratchet and pawl, and contacts operated by the electromagnetic coil coating with the armature, cam, ratchet and pawl, said contacts connected to the variable speed driving means whereby to increase or decrease the rotational speed of said variable speed driving means on energizing said coil, a second relay having normally open contacts controlled by an electromagnet, said contacts controlling the circuit including the coil of the first relay, a cold cathode tube having a plate circuit and a starter anode circuit, said plate circuit controlling the circuit including the electromagnet of the second relay, and contacts connected to the starter anode circuit of the cold cathode tube and mounted adjacent the path of the moving material, whereby the material will complete the starter anode circuit of the cold cathode tube and activate the relays.

12. In a device for feeding an endless length of moist material from one station to another, means for establishing and maintaining slack therein comprising in combination a constant speed driving means adapted to deliver the material from the first station, a variable speed driving means adapted to receive the material at the second station, a relay having an electromagnetic coil, an armature, cam, ratchet and pawl, and contacts operated by the electromagnetic coil coating with the cam, ratchet and pawl, one set of said contacts connected to the variable speed driving means whereby to increase or decrease the rotational speed of said variable speed driving means on energizing said electromagnetic coil, a cold cathode tube having a starter anode circuit and a plate circuit, said

plate circuit connected in series with the electromagnetic coil of the ratchet relay, contact means connecting the moving material to the starter anode circuit of the cold cathode tube, alternate contact means adjacent the path of the moving material adapted to contact the material and complete the starter anode circuit of the cold cathode tube, and a second set of contacts on the ratchet relay, adapted to shift the starter anode circuit of the cold cathode tube from one to the other of said alternate contacts mounted adjacent the path of the material.

13. A device for controlling a variable speed electric motor comprising a cold cathode tube having a starter anode, a plate and a cathode, alternate circuit completing means, a circuit including the starter anode and cathode of said tube and one of said circuit completing means, a normally open type relay having an electromagnetic coil and normally open contacts operated thereby, a circuit including the plate and cathode of the cold cathode tube and the coil of said normally open relay, a relay having an electromagnetic coil, an armature, ratchet, pawl and cam, and contacts operated thereby, a circuit including the coil of the ratchet relay and the contacts of the normally-open type relay, a fixed resistance, a power circuit for the variable speed motor including the fixed resistance and two contacts of the ratchet relay connected in parallel, whereby the said contacts will cut the fixed resistance in or out of the motor circuit on activation of the ratchet relay, and a second set of contacts on the ratchet relay connected to the circuit including the starter anode and cathode of the cold cathode tube, and adapted to shift said circuit from one to the other of the aforesaid circuit completing means.

14. In combination, a constant speed motor moving an endless length of moist cloth into a zone of slack, a variable speed motor moving the cloth on out of the zone of slack, an electrical contact connecting the moving cloth to one side of the starter anode circuit of the cold cathode tube, at least two electrodes connected to the other side of the starter anode circuit of the cold cathode tube, said electrodes spaced from the first contact in the direction of the length of the cloth, and spaced above and below the path of the moving cloth and adapted to intermittently engage by the cloth, whereby during such engagement the cloth may enter as an electrical conductor into the starter anode circuit of said tube and complete said circuit, a normally open type relay controlled by the anode circuit of the cold cathode tube, and a second relay having a ratchet and adapted to alternately increase or decrease the resistance in the power circuit of the variable speed motor, and simultaneously shift the starter anode circuit from one to the other of the electrodes disposed above and below the path of the cloth.

JAMES C. RYDER.
